UNITED STATES PATENT OFFICE.

HOWARD A. COOK, OF SOUTHFIELD, MASSACHUSETTS.

FLEXIBLE HIDE SHAFTING.

Application filed November 8, 1924. Serial No. 748,600.

To all whom it may concern:

Be it known that I, HOWARD A. COOK, a citizen of the United States, and resident of Southfield, county of Berkshire, and 5 State of Massachusetts, have invented certain new and useful Improvements in Flexible Hide Shaftings, of which the following is a specification.

This invention relates to flexible shafting 10 for transmitting rotary power through an angle, and more particularly to a flexible shafting made from animal hide.

A further object of the invention is to provide a flexible shafting of the above 15 nature which will be self-supporting, self-lubricating, form-sustaining and capable of extremely long wear.

A further object is to provide a flexible shafting which will not be likely to wear 20 through the surrounding casing, and which may be bent through relatively large angles without cracking or splitting.

A further object is to provide a flexible shafting of the above nature which will be 25 inexpensive to manufacture, practically unbreakable, and very efficient and durable in use.

With these and other objects in view 30 there have been illustrated on the accompanying drawings several forms in which the invention may be conveniently embodied in practice.

Fig. 1 represents a perspective view of a portion of the original strip of hide as it 35 appears in the process of being twisted into cylindrical shape.

Fig. 2 is a perspective view of the same after being twisted and consolidated.

Fig. 3 is a perspective view of a modified 40 form of flexible shafting having a central core of solid metal wire around which a strip of hide has been wrapped and consolidated.

Fig. 4 is a perspective view of another modified form of flexible shafting having a 45 central core of stranded metal wire around which a strip of hide has been wrapped and consolidated.

Fig. 5 is a perspective view of a flexible 50 cylindrical shafting made from a piece of rawhide by drawing it through a die without twisting.

Fig. 6 is a side view, with parts broken 55 away, of a portion of flexible shafting as it appears when connected with a speedometer.

Fig. 7 is a perspective view of a further modified form of flexible shafting constructed of a plurality of braided strands of hide. 60

Fig. 8 is a perspective view of a still further modified form of the invention constructed of two narrow strips of hide twisted together and consolidated. 65

Previous forms of flexible shafting for transmitting rotary power to speedometers, drills, clippers, and the like, have been of three main types; first, shafting made from soft pliable material, such as rubber or cat-gut; second, spiral wire coils; and 70 third, metal link chains. The use of the first type of shafting was subject to the disadvantage that it had to be inclosed in a tightly fitting supporting wrapper of tape, or the like, in order to give it sufficient 75 strength to permit it to rotate through an angle without collapsing or buckling. It was found, however, in the use of such shafting that the wrapper would quickly 80 wear off wherever the shafting was bent, due to its rubbing contact with the surrounding casing, making frequent renewals necessary. Consequently, this first type of 85 shafting has long ago been abandoned.

The second type of shafting, namely, 85 metal coiled wire, was quite delicate and complicated in construction. It was not only subject to rapid rusting, but also was quite liable to be readily broken, due to the rapid crystallization of the metal, caused 90 by the alternate stresses and strains to which all flexible shafting is subjected in use.

The third former type of flexible shafting, namely, metal link chains, was unsatisfactory on account of the excessive backlash, and also because the links were liable 95 to shear off and tear up the surrounding casing whenever the direction of rotation was reversed. Consequently, this type of 100 flexible shafting is also being rapidly discarded.

By means of the present invention the above and other disadvantages have been entirely avoided. This has been accomplished by forming the shafting from animal hides—producing a shafting which is self-supporting and form-sustaining, and which will be practically unbreakable under the repeated bending strains which it receives when in use. Moreover, the flexible shafting formed in accordance with the pres- 105 110

ent invention does not require any supporting wrapper to hold it in shape, and consequently, may be directly enclosed in the surrounding casing.

- 5 Referring now to the drawings in which like reference numerals denote corresponding parts throughout the several views, the numeral 10 (Fig. 1) indicates a narrow flat strip of rawhide in its original soft wet condition. By suitable machinery, not shown, the strip 10 is twisted before being dried into the form of a cylindrical rod 11 with the line of its abutting edges forming a right-hand helix. After the twisted rawhide rod 11 has dried and thereby consolidated and hardened, the surface of the rod is preferably smoothed by grinding in any suitable manner to make the shafting more uniform and to improve its appearance.
- 10 The flexible rawhide shafting may then be coated, if desired, with any suitable waterproof, lubricating, wear-resisting material, such as graphite, or may be treated with a suitable tanning solution to produce a coating of still greater flexibility.

When it is desired to use the flexible shafting, the end of the shafting at the right of Fig. 6, not shown, is connected in any suitable manner to the driving mechanism of an automobile or other source of power. The left-hand end 12 of the flexible shafting may be connected to a speedometer 13 or other instrument by means of a socket 14, into which the end of the shafting is fitted. The flexible shafting may be held in the socket in any suitable manner, as by means of a pin 15 passing through said socket 14 and said shaft 12.

15 In operation, when the shafting is to be used for transmitting heavy loads, the direction of rotation of the driving mechanism will preferably be such as to normally tend to twist the shafting in the same direction as it was originally twisted during the process of its manufacture. In this manner there will be no danger or possibility for the helical joints of the rawhide rod to spread open. It will be understood, however, that the flexible shafting will operate quite efficiently under ordinary loads even though the driving shaft is rotating in the reverse direction from that just mentioned.

20 While it is preferred to construct the flexible shafting out of untanned raw animal hides, it is to be understood that it is within the spirit of the invention to employ partly tanned hides or leather for this purpose, or if desired, the interior of the shafting may be raw untanned hide, while the outer surface may be tanned or otherwise treated to render the shafting moisture-proof and more flexible.

25 In some cases, where extremely large torsional stresses are to be transmitted, it may be advisable to strengthen the flexible shaft,

as by the means shown in Figs. 3 and 4. In Fig. 3, the flexible shaft 17 is strengthened by an interior solid rod 16, the hide in this instance being wound with a left-hand helix. Another form of strengthening rod 18 is 70 disclosed in Fig. 4, said rod 18 being formed from a plurality of strands of flexible metal wire. The stranded rod in Fig. 4 is encased within a rawhide core 19, which also has a left-hand twist. 75

In other cases, where the torsional stresses to be transmitted are of relatively small magnitude, the form of flexible shafting shown in Fig. 5 may be employed. In this form, the shafting 20 is formed by forcing 80 a piece of rawhide while in a soft wet condition longitudinally through a die without twisting.

In still other cases, where the combination of extreme strength and extreme flexibility 85 is desired, as when the shafting is required to pass around one or more sharp corners, the modified form shown in Fig. 7 may be employed. In this form, the shafting 21 is made up of a plurality of strands (four in 90 this instance 22, 23, 24, and 25) of hide, raw or tanned, braided or otherwise flexibly woven together in close relationship.

95 In other cases, where the highest degree of flexibility is desired, and where the maximum strength is not necessary, the modified type of shafting shown in Fig. 8 may be employed. This form of shafting is similar to the form shown in Fig. 2, but instead of being constructed by twisting a single strip of hide, it is made by winding together a plurality of strips (two in this instance, as indicated by the numerals 26 and 27). As will be noted, in the cross section of the shafting shown in Fig. 8, the line of clearance between the two twisted strips is curved, which fact causes the strips to be more securely locked together. 100

105 While there have been disclosed in this specification several forms in which the invention may be embodied, it will be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims. 110

115 Having thus fully described the invention, what is claimed as new, and for which it is desired to secure Letters Patent, is:

120 1. In a flexible shafting for transmitting rotary power, a casing, and a core within said casing, said core comprising a form-sustaining rod formed from a pair of strips of hide twisted helically into cylindrical shape with their edges in abutment. 125

130 2. In a flexible shafting for transmitting

rotary power, a casing, and a core within said casing, said core being formed from a plurality of strips of originally flat hide twisted into cylindrical shape and consolidated with their sides in abutment.

3. In a flexible shafting for transmitting rotary power, a casing, and a core within said casing, said core consisting of rawhide.

4. In a flexible shafting for transmitting 10 rotary power, a casing, and a core within said casing, said core consisting of a plurality of strips of animal hide bent while still soft until their side edges are in abutment, and when hardened, forming a consolidated cylindrical rod adapted to rotate 15 inside of said casing.

5. In a flexible shafting for transmitting rotary power, a casing, and a core within said casing, said core consisting of a consolidated rod of animal hide coated with graphite, said core being adapted to rotate loosely 20 within said casing.

6. In a flexible shafting for transmitting 25 rotary power, a casing, and a core within said casing, said core consisting of a con-

solidated rod of rawhide coated with water-proof, lubricating, wear-resisting material.

7. In a flexible shafting for transmitting rotary power, a casing, and a core within 30 said casing, said core consisting of a consolidated rod of self-supporting animal hide, said rod being adapted to rotate loosely within said casing.

8. In a flexible shafting for transmitting 35 rotary power, a casing, and a core within said casing, said core consisting of a consolidated rod of animal hide, said rod being self-supporting.

9. In a flexible shafting for transmitting 40 rotary power, a plurality of strips of animal hide twisted together into solidified self-sustaining form.

10. In a flexible shafting for transmitting 45 rotary power, a consolidated rod of animal hide, having its interior composed of relatively raw hide, and having its exterior treated with tannage.

In testimony whereof, I have affixed my signature to this specification.

HOWARD A. COOK.
